8 Claims. (Cl. 210—78)

This invention relates to centrifugation of materials, especially compressible fibrous materials, and has particular reference to an improved method and apparatus for filling the centrifuge with such material and emptying it of the centrifuged material.

In the processing of wool for textile use, for example, the wool is freed of wool fat and impurities by washing it with a suitable organic solvent, usually white spirits or the like. The wool is then freed as completely as possible of the washing liquid, generally and preferably by a centrifugation of the wet wool wherein the centrifugally separated liquid is recovered and returned to the washing operation.

Heretofore, filling the centrifuge with the wet wool and removing the dry wool from the centrifuge have been effected manually while the centrifuge rotor is stationary. To facilitate these operations somewhat, it is possible to place the wool in baskets which can be placed into and removed from the rotor. It is obvious, however, that these manual operations are laborious and time-consuming.

By the present invention, these manual operations are entirely replaced by a mechanical process which is automated to such extent that only supervision and setting of the automation, and possibly correction of the setting, are required for full operation of the plant. A further advantage of the invention is that the centrifuge filling and emptying apparatus can be used with previously installed, conventional centrifuges without requiring any modification thereof, and a complete automation of the centrifuge operation can easily be effected at reasonable costs.

Since the discharge and the filling are entirely mechanized, the centrifuge does not need to be opened at any moment during the operation, which ensures a better protection of the operators and facilitates the scavenging in the factory. Also, the problem of transportation of the centrifuged material is solved in an advantageous manner.

In the method of the present invention, the centrifuged material is discharged through an exhaust pipe which is introduced into the centrifuge rotor during operation, preferably in the axial direction of the rotor axis and within or in proximity to the body of material, while the rotor is rotating at reduced speed, and the exhaust pipe is withdrawn from the centrifuge after the centrifuged material has been discharged, the centrifuge then being refilled with material and the rotor accelerated to normal operating speed.

In the preferred method of the invention, two centrifuges are operated alternately in such way that each centrifuge is filled while the other is being discharged, and automatic devices control the alternate discharge and filling of the centrifuges.

According to the invention, the centrifuge filling and emptying apparatus comprises the aforesaid exhaust pipe

2

in the form of a tubular member arranged telescopically relative to an exhaust pipe line connected to the centrifuge. This tubular member is preferably displaceable axially so that it can be introduced into and withdrawn from the centrifuge rotor by a control means, the tubular member entering the rotating body of material at a region thereof located radially outward from the rotor axis and near the rotor wall against which the material is pressed centrifugally.

10 Further characteristics of the apparatus as well as its mode of operation are described more in detail below, reference being made to the attached drawing in which the single illustration is a schematic side-elevational view, partly in section, of a plant provided with two alternating operating centrifuges according to the invention.

15 The two centrifuges as illustrated, designated A and B, respectively, are strictly alike both in size, type and equipment. Therefore, corresponding parts of the two are marked with the same reference numerals, those for centrifuge A having the suffix "a" added.

20 Reference numeral 1 designates the housing of the centrifuge and 2 its rotor. A pipe 3 is telescopically arranged inside an exhaust pipeline 4 connected to the centrifuge from above and at one side of the vertical axis 25 of the rotor. Pipe 3 is displaceable axially (parallel to the rotor axis) so that it can be inserted into and withdrawn from the centrifuge rotor 2 through its open top. Alternatively, pipe 3 may be telescopically arranged outside the exhaust pipeline 4, so that the pipe 3 can be inserted in and withdrawn from the centrifuge rotor 2 30 eccentrically in relation to the rotor axis and radially within or in the proximity to the centrifuged material, which is pressed against the inside of the rotor wall by the centrifugal force.

35 The end 6 of the pipe 3 which faces the centrifuge is bevelled, preferably in such way that its edge plane forms an angle of about 45° with the nearest generating line of the rotor wall, which angle ensures optimum exhaust when discharging the centrifuge by approximating the

40 angle of the surface of the material. The insertion of pipe 3 into and its withdrawal from the centrifuge rotor are caused by control means comprising a pneumatically or hydraulically actuated cylinder 5 hinged at its upper 45 end to a container 10, as shown at 14, and a piston in the cylinder having a hinged connection 15 to the upper portion of pipe 3.

The end of the exhaust pipeline 4 which is remote from the centrifuge is connected to an exhaust pipeline 7 which is common to both centrifuges A and B, whereby pipeline 50 7 can be alternately connected to the one or the other centrifuge by switching a damper (not shown).

55 Reference numeral 8 designates a conveyor, shown schematically, which supplies the non-centrifuged stock to the plant. This stock is distributed alternately to the centrifuges A and B from conveyor 8 by a reversible conveyor 9. The conveyor 9 supplies the non-centrifuged stock into the open top of a funnel-like storage and balance container 10, the bottom outlet of which opens into the rotor 2 centrally thereof and just below its upper edge. The filling of the centrifuge with non-centrifuged stock is controlled by a bisected damper 11 arranged in the outlet of the container 10 and actuated by control means comprising a pneumatically or hydraulically actuated cylinder 12. The latter is secured to container 10 and has a piston 16 pivotally connected to hinged elements 17

and 18 for actuating the respective sections of the damper 11.

The peripheral wall of the rotor 2 is provided with small perforations (not shown) so that the separated washing liquid can be ejected centrifugally and collected in the centrifuge housing 1, from which it may be discharged through pipe 20. The centrifuge housing 1 may be provided with a cover (not shown) through which the exhaust pipe 4 as well as the outlet of the container 10 penetrate slightly into the centrifuge rotor 2. In order to allow external air to be sucked into the centrifuge during the discharge process, such cover or the top of the centrifuge housing 1 can be provided with adjustable louvers (not shown). It will be understood that rotor 2 is supported and driven from below by a vertical shaft 21 projecting centrally through the bottom of stationary housing 1.

In operation, damper 11 is operated by its control means 12 to fill rotor 2 with the wet wool or other material while the rotor is being accelerated from its reduced emptying speed to its normal operating speed. The high speed centrifuging is then carried out for a time period sufficient to effect the desired removal of washing liquid from the material through the perforated rotor wall, after which the rotor speed is reduced and pipe 3 is lowered axially into the rotor by operation of the control means including cylinder 5. This discharge is facilitated by the tendency of the centrifuged material to expand radially inward toward the rotor axis as the centrifugal force is reduced due to reduction of the rotor speed. The material thus scooped by pipe 3 from the rotating body of material in rotor 2 is sucked continuously through pipe 3 and pipeline 4 into exhaust pipeline 7 common to both centrifuges, the damper of line 7 being positioned, of course, to open the latter to pipeline 4 while closing it from pipeline 4a.

When pipe 3 starts to be lowered into rotor 2 of centrifuge B for emptying the latter, as previously described, pipe 3a of centrifuge A is rapidly withdrawn from the corresponding rotor 2a, by operation of control means 5a, the discharge from rotor 2a having now been completed. The speed of rotor 2a is then accelerated to full operating speed while a new batch of feed stock is introduced to rotor 2a from container 10a, under control of the corresponding damper control means 12a. After rotor 2a has been driven at high speed for the required time period, it is emptied in the manner described in connection with centrifuge B, while the latter is being refilled.

As mentioned previously, the above-described apparatus is operated fully automatically. That is, the displacements of the pipes 3 and 3a into and out of the centrifuges, the decrease and increase of the rotational speed of the centrifuges, the switching over and the control of the damper in the exhaust pipeline 7 and of the dampers 11 and 11a, and the reversing of the conveyor 9, are controlled and synchronized by a suitable program-unit so that the centrifuges operate alternately as previously described.

The invention is not limited to the treatment of compressible and fibrous materials but can also be used in the centrifugation of all kinds of solid materials suitable for air-borne transportation.

We claim:

1. In the centrifugation of a compressible fibrous material with the use of a centrifuge rotor and an exhaust pipe, the method which comprises filling the rotor with said material while accelerating the rotor to an operating speed for centrifuging said material, forming an annular body of centrifuged material in the outer part of the rotor, introducing said pipe into the rotor and in proximity to said body while reducing the rotor speed, inducing a suction in said pipe whereby material is sucked from the rotating body by the pipe and discharged from the rotor, withdrawing said pipe from the rotor, and refilling the rotor

with a new batch of said material while accelerating the rotor to said operating speed.

2. Apparatus for centrifuging compressible fibrous material, which comprises a centrifugal rotor, a discharge pipeline leading from the rotor, a tubular suction member telescopically fitted relative to the pipeline and movable axially thereof into the rotor to suck centrifuged material from the outer part of the rotor, suction means communicating with said pipeline and tubular member, and control means for moving the tubular member relative to the pipeline and into the rotor and for withdrawing the tubular member from the rotor relative to the pipeline.

3. Apparatus as defined in claim 2, in which the rotor axis is vertical and the end of said tubular member adjacent the rotor is bevelled to form an acute angle with the nearest generating wall of the rotor, which angle approximates the angle of the surface of the centrifuged material.

4. Apparatus as defined in claim 2, in which said control means include an actuating cylinder and piston.

5. Apparatus as defined in claim 2, in which said tubular member is offset laterally from the rotor axis and movable parallel to said axis.

6. Apparatus as defined in claim 2, in which said tubular member is offset laterally from the rotor axis and movable parallel to said axis, the apparatus comprising also a feed container for said material having an outlet opening into the rotor on said axis.

7. Apparatus for centrifuging compressible fibrous material, which comprises a pair of centrifugal rotors, a discharge pipeline leading from each rotor, a tubular suction member telescopically fitted relative to each pipeline and movable axially thereof into the corresponding rotor to suck centrifuged material from the outer part of the rotor, suction means communicating with each pipeline and each tubular member, control means for moving each tubular member relative to the corresponding pipeline and into the corresponding rotor and for withdrawing each tubular member from the corresponding rotor relative to the corresponding pipeline, said control means being adapted to move each tubular member independently of the other tubular member, a discharge pipe common to said rotors and to which said discharge pipelines lead, and supply control means for admitting material alternately to said rotors.

8. In the centrifugation of a compressible fibrous material with the use of first and second centrifugal rotors and first and second exhaust pipes for the respective rotors, the method which comprises repeatedly performing a first series of steps including filling the first rotor with said material from a supply source, accelerating the first rotor to an operating speed for centrifuging said material as the first rotor is being filled, forming an annular body of centrifuged material in the outer part of the filled first rotor, introducing the first pipe into the first rotor and in proximity to said body therein while reducing the first rotor speed, inducing a suction in said first pipe whereby material is sucked from the rotating body by the first pipe and discharged from the first rotor, and withdrawing said first pipe from the first rotor prior to refilling of the first rotor, and repeatedly performing a second series of steps including filling said second rotor with material from said source after the introduction of the first pipe into the first rotor and prior to refilling the first rotor, accelerating the second rotor to an operating speed for centrifuging said material as the second rotor is being filled, forming an annular body of centrifuged material in the outer part of the filled second rotor, introducing the second pipe into the second rotor and in proximity to said body therein while reducing the second rotor speed and while effecting the withdrawal of the first pipe from the first rotor, inducing a suction in the second pipe whereby material is sucked from the rotating body in the second rotor by the second pipe and discharged from the second rotor, and withdrawing the

second pipe from the second rotor during reintroduction of the first pipe into the first rotor and prior to refilling the second rotor.
